(57) **CLAIM**

The ornamental design for a holder for a handset, as shown and described.

DESCRIPTION

FIG. 1 is a perspective view of a holder for a handset showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of a second embodiment of a holder for a handset showing my new design;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The broken lines shown in FIGS. 1–7 that are immediately adjacent to the shaded areas represent boundaries of the claim of the first embodiment. The broken lines and unshaded surfaces bounded by broken lines form no part of the claim of the first embodiment.
